GRAIN SAMPLING DEVICE
Paul J. McGinn, Box 393, Ipswich, S. Dak.
Filed Apr. 30, 1962, Ser. No. 190,929
6 Claims. (Cl. 73—425.2)

This invention relates to a grain-type sampling device and more particularly to a probe-type grain sampling device having a sectional handle structure.

An object of this invention is to provide a novel grain sampling device, of simple and inexpensive construction, including a grain sampling probe having an elongate sectional handle structure arranged and constructed for ready assembly to thereby permit a user to very substantially reduce the time ordinarily required for performing the grain sampling operation.

Another object of this invention is the provision of a novel and improved sectional handle structure for use in conjunction with grain type probes, and including a plurality of elongate handle sections coupled together in end-to-end relation, readily releasable locking means interlocking adjacent handle sections together, and lock guide means for facilitating locking of the locking means whereby the handle structure may be very quickly disassembled in section-by-section order.

A more specific object of this invention is the provision of a sectional handle structure for use in conjunction with a grain sampling probe and including elongate upper and lower sections and a plurality of similar intermediate sections interconnected together in end-to-end relation, and wherein adjacent sections are interconnected together by male and female socket members, the latter having releasable locking means positively but releasably locking the interconnected sections together.

These and other objects and advantages of my invention will more fully appear from the following description made in connection with the accompanying drawing wherein like character references refer to the same or similar parts throughout the various views, and in which:

FIG. 1 is a side elevational view of my invention fore-shortened for clarity;

FIG. 2 is a longitudinal sectional view on an enlarged scale taken approximately along line 2—2 of FIG. 2 and looking in the direction of the arrows; and

FIG. 3 is a side view partly in section and partly in elevation on enlarged scale of the grain sampling probe.

Referring now to the drawing and more specifically to FIG. 1, it will be seen that one embodiment of my grain sampling device designated generally by the reference numeral 10, is thereshown. This sampling device is of the type employed in sampling various kinds of grain such as wheat, corn, oats and the like normally stored in storage structures such as bins, silos and the like.

The grain sampling device 10 includes a grain sampling probe 11 and an elongate sectional handle structure 12 detachably secured to the probe. The probe 11 is of hollow, generally cylindrical construction and has a lower pointed end 12 to facilitate penetration of the grain into which the probe is forced during the sampling operation. The upper end of the probe 11 is opened to permit the entrance of grain into the probe during the sampling operation. An elongate pin 14 traverses the interior of the probe and is affixed to opposed wall portions thereof in close proximity to the open upper end.

A closure cover 15 is shiftable connected to the pin 14 and serves to open and close the upper end of the probe 11. This closure cover 15 is provided with a depending annular flange 16 which fits around the upper circumferential edge portion of the probe when the cover 15 is in closing relation therewith. The underside of the cover 15 has a centrally located U-shaped element 17

2

rigidly affixed thereto and an elongate ring-type link 18 is shiftable connected to the transverse pin 14 and the U-shaped element 17. Thus it will be seen that the cover 15 and the probe 11 are interconnected for relative movement therebetween. It is also pointed out that the probe 11 and cover 15 therefor are preferably constructed of a suitable rigid material such as metal or the like.

The sectional handle structure 12 is comprised of a lower handle section 19, a plurality of intermediate similar handle sections 20, and an upper handle section 21 interconnected together in end-to-end relation. The lower end portions of the lower section 19 terminate in a reduced threaded male member 22 for threadedly engaging a threaded female member 15a on the cover 15, as best seen in FIG. 3. All of the sections are of substantially tubular construction and are detachably connected together in end-to-end relation for ready assembly and disassembly. The respective inner engaging end portions of adjacent sections each define a coupling connector.

Referring again to FIG. 1, it will be seen that all of the intermediate sections are of substantially identical construction while the upper terminal portion of the upper section 21 is provided with a hand gripping element 21a to facilitate extension and retraction of the grain probe 11 into and out of the grain being sampled. The upper end of the lower section 19 and the respective upper ends of each of the intermediate sections each define an axially extending, upwardly opening socket member 23, as best seen in FIG. 2. In this connection it is pointed out that although FIG. 2 illustrates the interconnected relation between adjacent intermediate sections it is pointed out that the socket member defined by the upper end of the lower section is of identical construction.

Rigidly affixed to the lower end of the upper section 21 and the respective lower ends of each of the intermediate sections 20 is a male socket-engaging member 24. Again, it is pointed out that the male socket-engaging member 24 is of identical construction in the upper section 21 and in each of the intermediate sections 20 and that the illustration of FIG. 2 while showing one such socket-engaging member is adequate for the description of this structure. It will be noted that the male socket-engaging member 24 is of reduced size and is fixedly retained within the lower end portion of its associated section by means of rivets 25. Each of the male socket-engaging members 24 is received within the socket member 23 of the next adjacent section to define the coupling connection for interconnecting the various sections in end-to-end relation.

Means are provided for positively but releasably locking the coupling connections between adjacent sections in interlocked relation and this locking means includes a resilient lease spring element 26 secured to the exterior surface of the socket member 23 for each coupling connection. It will be seen that the lower portion of the resilient lease spring 26 is secured to its associated socket member by means of rivets 27 and that the upper end of the lease spring has locking element 28 secured thereto. Each of the socket members 23 has an aperture 29 therein to permit its associated locking element 28 to project therethrough so that the locking element extends radially inwardly of the socket member.

Each of the male socket engaging members 24 has a locking recess or aperture 30 extending diametrically through the lower portion thereof. This locking recess 30 serves to receive the locking element 28 therein for positively but releasably locking the female socket member and the male socket-engaging member of each coupling connection into interlocked relation. To this end, it will be noted that the locking element 28 will be urged radially inwardly by the spring 26 so that the locking ele-

ment will be retained in locked relation but it is pointed out that the locking element may be forcibly retracted to readily unlock the socket and socket engaging members. It will also be noted that the lower terminal portion of each male socket engaging member is tapered, as at 24, and this tapered end serves to cam the locking element 28 of its associated socket member radially outwardly when the socket-engaging member is inserted into the socket. Thus it will be seen that the locking element and recess actually constitute a snap coupling locking mechanism.

Means are also provided for guiding and positioning the locking recess 30 in radial alignment with the locking element 28 during the locking operation. To this end, it will be seen that each of the male socket-engaging members 24 is provided with a pin 31 extending transversely therethrough and affixed thereto. It will be noted that the pin 31 is spaced from the lower terminal portion of its associated male socket-engaging member and projects radially outwardly from opposite sides thereof.

Each of the socket members 23 is provided with a pair of diametrically opposed slots 32 each extending axially from the end of the socket member and terminating in an angular offset portion 33. During the locking operation, the radially extending portions of the pin 31 will be positioned within the slots 32 and when the section is revolved to position the radially extending portions of the pin 31 into the offset portions 33 of the slots, the locking element 28 and locking recess will be positioned into radial alignment to thereby permit the locking element to be snapped into the locking recess. It will also be noted that the obstructing surface 34 defined by the offset portion of each slot serves to lock the radial extending portions of the pin 31 against axial movement so that in effect the pin and slot of each coupling connection not only serves as a means for positioning the locking elements in radial alignment but also comprises an additional locking means.

When sampling granular material, such as wheat or the like, the sampler will take samples at a number of different locations of the wheat stored in the storage receptacle. In order to obtain the good representative sample of the storage grain, the sampler will take a predetermined number of samples at various depths at each location. In the conventional storage receptacles employed for storing wheat, corn and the like, samples are taken at four different depth levels and at five different points of location so that a fair representative sampling of the granular material is obtained.

When the sampling grains in these conventional structures, the sampler completely assembles the probe in preparation of acquiring a sample at a predetermined location and at the lowest depth of this location. Ordinarily the handle structure when assembled to take a sample at the deepest depth will include an upper section, two intermediate sections and a lower section, the latter being secured to the grain probe. When so assembled, the sampling device is urged downwardly through the grain to substantially the full length of the handle structure. It is pointed out that the grain probe will be forced against the cover as the probe is urged downwardly through the granular material. When the probe is extended into the grain substantially the full length thereof, agitation of the handle causes relative shifting movement between the probe and cover to permit grain to fill the interior of the probe. The handle is then retracted to remove the grain retained in the probe.

In order to acquire the sample at the next level, the sampler merely removes one of the intermediate sections 20 from the handle structure and reassembles the handle structure and takes a sample of the next lower level. This operation is repeated until the required number of samples is obtained from the various levels of a given location. The readily releasable locking means and the guide means permit ready assembly and disassembly of the handle with a minimum of effort and in a minimum of

time. In the conventional sampling devices, the various sections thereof are threadedly interconnected and continued axial thrust on the threaded connection will cause the threads thereof to fail which results in probes being lost. It is further noted that the time required to assemble and disassemble the handle structure of the instant invention is substantially less than the time required in disassembling the conventional threaded handle structures. Furthermore, the threads of the threaded couplings in the conventional sampling devices very often tend to bind and disengagement of the threaded connections often results in a very time consuming operation.

It will further be seen that each coupling connection is not only secured and positively locked by the locking element 29 and locking recess 30 thereof, but that the pin 31 and slot 32 often serve to lock the interconnected sections together.

From the foregoing, it will be seen that I have provided a novel sampling device and which includes a sectional handle structure which may be readily assembled and disassembled with a minimum of effort and in a minimum of time thereby permitting a great reduction in the cost of labor during the sampling operation.

It will also be seen from the preceding paragraphs that while the various sections of the handle structure are capable of ready assembly and disassembly, these sections are so interconnected that even if the cooperating locking element and recess become disengaged, the cooperative relation between the pin 31 and the offset lock portion 33 of each coupling connection also serves to retain the sections in locked relation.

Thus it will be seen that I have provided a novel sampling device which is not only of simple and inexpensive construction, but one which functions in a more efficient manner than any heretofore known comparable devices.

It will, of course, be understood that various changes may be made in the form, details, arrangement, and proportions of the various parts without departing from the general scope of my invention.

What is claimed is:

1. A sampling device for use in sampling particulate material such as grain and the like,

said device comprising a grain type sampling probe having a pointed lower end and an open upper end, a closure cover shiftably connected to said probe for opening and closing said open upper end, an elongate sectional handle structure for said probe, and including elongate upper, lower and intermediate sections detachably connected together in end-to-end relation,

the lower end portion of said lower section being detachably connected to the closure cover in fixed relation therewith and the upper end portion of said upper section having a transversely extending hand grip element affixed thereto,

the respective end portions of said intermediate section, the lower end portion of the upper section, and the upper end portion of said lower section each defining a coupling connector,

one coupling connector on said intermediate section and one of the coupling connectors of said upper and lower sections comprising an axially extending generally cylindrical socket member, the other connector of said intermediate section and the other connector of one of said upper and lower sections comprising a generally cylindrical shaped socket engaging member for ready insertion into the socket member of the adjacent section to define a coupling connection, releasable locking means for releasably locking said coupling connections,

said locking means comprising a radially extending locking element mounted on one of said socket engaging and socket member of each coupling connection and a radially extending recess in the other of

said members for receiving the locking element therein, said locking element when disposed in locking relation in said locking recess extending radially inwardly of the socket defined by said socket member, and each coupling connection including a slot formed in one of said members and in the same member as said locking element, said slot for each coupling connection extending first axially from the end of said member and terminating in an angular offset portion and being spaced axially of the locking element of the associated member, a radially extending pin on the other of said members of each coupling connection which when disposed within said angular offset portion positioning said locking element in radial alignment with its associated recess to thereby facilitate locking of said coupling connection, said pin being spaced axially of the locking recess of the associated member, and each of said coupling connections being readily disconnectible upon axial retraction of its locking element from the associated locking recess and thereafter revolving the socket and socket engaging members relative to each other.

2. A sampling device for use in sampling particulate material such as grain and the like, said comprising a grain type sampling probe having a pointed lower end and an open upper end,

a closure cover shiftably connected to said probe for opening and closing said upper end, an elongate sectional handle structure for said probe and including elongate upper, lower and a plurality of intermediate sections detachably interconnected together in end-to-end relation, the lower end portion of said lower section being detachably connected to the closure cover in fixed relation therewith and the upper end portion of said upper section having a transversely extending hand grip element affixed thereto, the upper end portion of said lower section and the respective upper end portions of said intermediate section each defining an upwardly opening generally cylindrical socket member,

the lower end portion of the upper section and the respective lower end portions of each of said intermediate sections each defining a generally cylindrical socket engaging member for ready insertion into the socket member of the next adjacent section whereby said cooperating sockets and socket engaging members define a coupling connection, releasable locking means for releasably locking said socket member and cooperating socket engaging member together, said locking means comprising a radially extending locking element mounted on one of said socket engaging and socket members of each coupling connection and in a radially extending recess in the other of said members for receiving the locking element therein, said locking element when in locked relation within said recess extending radially inwardly of the socket formed by said socket member,

and each coupling connection including a slot formed in one of said members and in the same member on which said locking element is mounted, said slot of each coupling connection extending first axially from one end of said member and terminating in an angular offset portion, said slot being spaced axially from said locking element on the associated member, a radially extending pin on the other of said members of each coupling connection which when disposed in said angular offset portion of its associated slot positioning said locking element in radial alignment with its associated locking recess to thereby facilitate locking of said coupling connection, said pin being spaced axially from the locking recess of the associated member,

and each of said coupling connections being readily

disconnectible upon axial retraction of its locking element from the associated locked recess and thereafter revolving the socket and socket engaging members relative to each other.

5 3. A sectional handle structure for use in conjunction with a grain sampling probe having a pointed lower end and an open upper end and having a closure cover shiftably connected thereto for opening and closing said open upper end,

10 said sectional handle structure including an elongate upper section, a plurality of intermediate sections and a lower section detachably connected together in end-to-end relation,

15 the lower end portion of said lower section having means thereon for detachable connection to the closure cover of a probe in fixed relation therewith and the upper end portion of said upper section having a transversely extending hand grip element affixed thereto,

the upper end portion of said lower section and the respective upper end portions of each of said intermediate section each defining an upwardly opening generally cylindrically shaped socket member, the lower end portion of said upper member and the respective lower end portions of each of said intermediate members each defining a generally cylindrically shaped socket engaging member for ready insertion into the socket member of the adjacent section,

releasable locking means for releasably locking each of the socket members with its associated socket engaging member, said locking means comprising a spring urged locking pin shiftably mounted on each of said socket members for radial shifting movement relative thereto and radially of the opening defined by the socket member, each of said socket engaging members having a radially extending recess therein for receiving the axially extending locking element of the associated socket member therein, each locking element when in locked relation in the associated locking recess extending radially inwardly of the socket defined by the associated socket member,

each of said socket members having an elongate slot formed therein and extending axially from the end of the socket member and terminating in an angular offset portion, said slots being spaced axially upwardly from the locking element of the associated locking member, each of said socket engaging members having a radially extending pin thereon which when disposed within the angular offset portion of its associated slot positioning said locking element in radial alignment with its associated recess thereby facilitating locking of cooperating socket and socket engaging members, said pin being spaced axially of said radially extending recess of the associated socket engaging member,

and said cooperating socket and socket engaging members being readily disconnectible upon axial retraction of its locking element from its associated recess and thereafter revolving the socket and socket engaging members relative to each other.

4. The structure as defined in claim 3 wherein the lower terminal portions of each of said socket engaging members is tapered to define a camming surface for camming the locking element of the cooperating socket member axially outwardly upon insertion of a socket engaging member into one of said socket members.

5. The structure as defined in claim 3 wherein each of said locking elements is provided with a resilient spring element for normally urging the locking element radially inwardly.

6. A sampling device for use in sampling particulate material such as grain and the like, said device comprising a grain-type sampling probe

75

having a pointed lower end and an open upper end, a closure cover shiftably connected to said probe for opening and closing said open upper end, an elongate sectional handle structure for said probe and including an elongate upper section, a plurality of substantially similar elongate intermediate sections, and an elongate lower section connected together in end-to-end relation, 5 the lower end portion of said lower section having means thereon detachably connected to said closure cover in fixed relation therewith and the upper end portion of said upper section having a transversely extending hand grip element affixed thereto, the upper end of said lower section and the respective upper ends of said intermediate sections each defining 10 a generally cylindrical upwardly opening socket member, the lower end of said upper section and the respective lower section of said intermediate section each defining a generally cylindrically shaped socket engaging member for ready insertion into the socket member of the adjacent section, 15 releasable locking means for releasably locking said cooperating socket and socket engaging members in interlocked relation, said locking means comprising a plurality of locking elements each mounted on one of said socket members in radially extending relation therewith and being radially shiftable relative thereto, each of said socket engaging members having a radially extending recess therein for receiving the locking elements of the associated socket members therein, 20 a plurality of elongate resilient spring elements each mounted on one of said socket members and extending longitudinally thereof and each spring element being connected to one of said locking elements and disposed normally thereto for normally urging the same radially inwardly and into its associated locking recess, each locking element when in locked relation 25

30

in the associated locking recess extending radially inwardly of the socket defined by the associated socket member, each of said socket members having a pair of opposed slots formed therein, each of said slots extending first axially from the end of said socket member and terminating in an angular offset portion, each of said slots being spaced axially upwardly from the upper end of the spring element on the associated socket member, a pin extending diametrically through each of said socket-engaging members and having terminal portions thereof extending radially outwardly of the socket engaging member which when disposed within the angular offset slot portions positioning the locking element in radial alignment with its associated recess and thereby facilitating locking of cooperating socket and socket engaging members, each pin being spaced axially from the locking recess on the associated socket engaging member, and each of said cooperating socket and socket engaging members being readily disconnectable upon axial retraction of its locking element from the associated locking recess and thereafter revolving the socket and socket engaging members relative to each other.
